United States Patent Office.

W. W. WORMOOD, OF DUBUQUE, IOWA, ASSIGNOR TO HIMSELF AND C. HATHAWAY, OF SAME PLACE.

Letters Patent No. 99,616, dated February 8, 1870.

IMPROVEMENT IN FARE-BOXES FOR STREET-CARS.

The Schedule referred to in these Letters Patent and making part of the same

To all whom it may concern:

Be it known that I, W. W. WORMOOD, of Dubuque, in the county of Dubuque, and State of Iowa, have invented a new and improved Pay-Box; and I do hereby declare that the following is a full, clear, and exact description thereof, which will enable others skilled in the art to make and use the same, reference being had to the accompanying drawings, forming part of this specification.

The object of this invention is to provide an improved construction and arrangement of that class of pay-boxes for street-cars, omnibuses, &c., wherein the fares are deposited by the passengers, and so arranged that they may be seen by the conductor, but so that he may not have access to the money or tickets deposited.

The invention consists in an improved arrangement for discharging the fares from the first receptacle and depositing and securing them in the space below, as is required to keep the said first receptacle clear for the better inspection of the fares as they are deposited, and to prevent access thereto by the conductor.

Figure 1 represents a side elevation of my improved pay-box;

Figure 2 represents an opposite side view;

Figure 3 represents a sectional elevation, taken on the line $x x$ of fig. 4; and

Figure 4 represents a sectional elevation, taken on the line $y y$ of fig. 3.

Similar letters of reference indicate corresponding parts.

I propose to employ a sheet-metal case or box, A, preferably of circular form, for the reception of the fare, and arranged on trunnions B, so as to oscillate thereon.

In the top of this case, which is to be placed in an opening through the wall of the car, are orifices C D, for depositing the fare, and on the side next to the driver is the glass or other transparent substance E, to permit the driver to inspect the fares as they are deposited upon the curved shelf F, below the said ori-

fices, for first receiving and temporarily holding the fare until inspected. This shelf is so arranged relatively to the case, as to prevent the escape of the fares to the space G below, except at one end thereof, adjacent to the inner side of the periphery-wall of the said case, at H, and the case must be turned on its axis to bring the point H of the shelf low enough for the contents to slide off into the said space below.

Below this passage, at H, another shelf, I, is placed and so arranged as to receive the fares and hold them until the box is turned back, when they slide off into the bottom toward the closed end of the shelf H, from which it is impossible to remove them by any devices inserted at the orifices C D, owing to the relative arrangements of the two shelves.

The dotted lines II' I' indicate the positions of these two shelves when the box is turned for discharging from the shelf F.

K represents the door for removing the fares. It may be locked or secured in any preferred way.

L represents a stop-bar, and N O stops on the box, to strike against it to arrest the movement of the box in each direction, at the proper points, and P is a knob for turning it.

The box may be weighted or otherwise arranged to maintain the receiving-orifices at the top.

Having thus described my invention,

I claim as new, and desire to secure by Letters Patent—

A circular or other formed pay-box, arranged for oscillation upon trunnions, and provided with the receiving-shelf F, guard-shelf I, and otherwise arranged substantially as specified.

The above specification of my invention signed by me, this 18th day of June, 1869.

W. W. WORMOOD.
